UNITED STATES PATENT OFFICE.

JASPER L. GRAY, OF GASTONIA, NORTH CAROLINA.

CONVEYER-PIPE CLEANER.

Application filed November 21, 1927. Serial No. 234,718.

This invention is an improvement in cleaners for pipe conveyers, and more particularly in a cleaner especially designed for cleaning cotton during its passage through a pneumatic conveyer.

Cleaners of the character in question are interposed in pneumatic conveyers, with the object of screening from the cotton during its passage sand, dirt, motes, and the like, 10 carried by the cotton, the cotton being passed over a grid through which such matter may fall.

In the usual construction, the grids quickly become clogged, thus lessening their efficiency. The openings in the grids are small, 15 and easily clogged by foreign bodies, so that the effective area of the screen is lessened to a greater or less extent.

Cleaners of the character in question are 20 usually provided with a receptacle for the foreign matter below the grid. In this receptacle there is a continuous agitation due to the air current in the conveyer, and a part of the contents thereof are drawn back into 25 the circulation, so that the efficiency of the cleaner as a dirt remover is greatly lessened.

One of the primary objects of the present invention is the provision of a cleaner, where- 30 in a grid is used, of a character such that the air draft will vibrate the same, to obtain suf- ficient agitation to prevent clogging, and to dislodge foreign matter which may be caught in the grid.

Another object is the provision of a form 35 of receptacle such that agitation therein due to the air circulation is reduced to a minimum, thereby to prevent suction of the removed foreign matter into the circulation.

Another object is the provision of a simple 40 and inexpensive construction, capable of interposition in the usual character of conveyer, and with as slight possible departure from accepted constructions, as is consistent with attainment of the end sought.

With these and other objects in view the 45 invention consists in the construction and novel combination of parts fully described hereinafter, illustrated in the accompanying drawings, and pointed out in the claims ap- 50 pended hereto, it being understood that various changes in the form, proportion, size and minor details of construction within the scope of the claims, may be resorted to with-

out departing from the spirit of the invention.

55

In the drawings forming a part hereof:

Fig. 1 is a longitudinal section of a pneumatic conveyer provided with the improved cleaner.

Fig. 2 is a section on the line 2—2 of Fig. 1.

Fig. 3 is an enlarged detail of the grid or screen.

The present embodiment of the invention is shown in connection with a pneumatic conveyer 1 of usual construction, the said conveyer including a pipe of substantially circular cross section through which the cotton is blown by a suitable air compressing or exhausting device.

At suitable intervals in the length of the 70 pipe the cleaners are arranged. Each of the said cleaners includes a box shaped structure having side walls 2, usually of wood, and end walls 3, which may be partly of wood, and partly of metal as shown. Instead of being 75 circular at the cleaner, the pipe is inverted trough shape, as indicated at 4, the side walls of the trough shaped portion diverging at substantially a right angle as shown, and abutting the sides of the grid to be later de- 80 scribed.

The structure also includes a plurality of doors 6, forming the bottom of the structure, each door being hinged to one side wall as indicated at 7, and having a detachable 85 connection with the other wall, by means of latch mechanism indicated at 8, in the present instance a bolt or bolts. By releasing the latches, the doors may be opened to remove the accumulation of foreign matter in 90 the structure.

In order to minimize agitation in the structure, it being understood that the said structure is separated from the portion of the pipe through which the cotton travels by means of the grids or screens to be later de- 95 scribed, baffles 9 are arranged transversely of the structure at suitable intervals, the said baffles dividing the structure into a plu- 100 rality of compartments.

One of the doors 6 is provided for each compartment, so that each compartment may be cleaned independently of the other, and a cleaner unit may include a plurality of the compartments, as for instance three in 105 the present instance. At the middle com-

partment, the portion 4 of the conveyer has a cleanout hole 10, enabling access to this portion of the pipe or conveyer.

A grid or screen is arranged between each compartment of the cleaner and the body of the pipe. Each of these grids is composed of a plurality of substantially parallel resilient steel bars 11, of sufficient thinness to be continually vibrated by the air current traveling through the pipe, and by the cotton moving past the bars. The bars are relatively closely spaced, and extend the full width of the box structure, and are connected at their ends by longitudinally extending plates 12.

The structure and the side plates of the grids are connected to the conveyer, by means of straps 13, which are riveted to the portion 4 of the pipe, to the side plates of the grid, and to the side walls of the structure, as indicated at 14, 15 and 16, respectively. Thus the cleaner as a whole is supported by the conveyer. The strips 3 extend to the lower edges of the side walls 2, and do not interfere with the operation of the doors.

Referring particularly to Fig. 3, it will be noticed that the bars 11 of all of the grids are inclined slightly from the vertical, the inclination being about 15° toward the inlet end of the conveyer. Thus the bars are in the best possible position to dislodge the foreign matter from the cotton, and to deflect it into the box structure.

The inclination also facilitates vibration of the bars. So placed the bars offer a slight hindrance to the passage of the cotton, agitating the same in the conveyer, and increasing the dirt dislodging function. The inclined arrangement tends to deflect a portion of the air current through the grid, and this deflected portion acts not only to clean the grid, but to give increased vibration.

The baffles minimize the agitation in the box structure by the air current, so that the foreign matter which falls in the compartments remains, and is not carried back into the circulation. The improved cleaners may be made of any desired length, each with as many compartments as may be desired. The baffles may be spaced as close as may be necessary. In practice each compartment is about two feet in length.

The cleaner is about twelve feet overall, having five partitions, which create a vacuum effect preventing the motes and other like particles from being drawn back into the cotton by the draft of the fan. With this length of cleaner there should be four hand hole cleanouts 10, which provision enables the operator to reach any part of the cleaner without difficulty.

What is claimed as new is:—

1. In a pneumatic conveyer pipe cleaner, a grid adapted to be inset in the bottom of the pipe to form a part of the wall thereof, said grid including bars relatively wide and rela-

tively thin to be vibrated by the current of air passing thereover through the conveyer pipe, arranged in parallel spaced relation, and inclining slightly from the vertical toward the inlet end of the pipe.

70

2. In a pneumatic conveyer pipe cleaner, a grid adapted to be inset in the bottom of the pipe in horizontal position and to form a part of the wall thereof, said grid including relatively wide and closely spaced bars arranged in spaced parallel relation and inclined slightly from the vertical toward the inlet end of the pipe whereby to provide a drag for the moving cotton, and to deflect a part of the current through the grid, said bars resilient and relatively thin to be vibrated by the air current for the purpose specified.

75

3. In a pneumatic conveyer pipe cleaner, a grid adapted to be inset in the bottom of the pipe in horizontal position and to form a part of the wall thereof, said grid including relatively wide and closely spaced bars arranged in spaced parallel relation and inclined slightly from the vertical toward the inlet end of the pipe whereby to provide a drag for the moving cotton, and to deflect a part of the current through the grid, said bars resilient and relatively thin to be vibrated by the air current for the purpose specified, and a box structure of which the grid forms the top for receiving foreign matter passing through the grid.

80

4. In a pneumatic conveyer pipe cleaner, a grid adapted to be inset in the bottom of the pipe in horizontal position and to form a part of the wall thereof, said grid including relatively wide bars arranged in spaced parallel relation and inclined slightly from the vertical toward the inlet end of the pipe whereby to provide a drag for the moving cotton, and to deflect a part of the current through the grid, said bars resilient and relatively thin to be vibrated by the air current for the purpose specified, and a box structure of which the grid forms the top for receiving foreign matter passing through the grid, said box having baffles extending transversely thereof between the grid and the bottom of the structure.

90

5. In a pneumatic conveyer pipe cleaner, a grid adapted to be inset in the bottom of the pipe in horizontal position and to form a part of the wall thereof, said grid including relatively wide bars arranged in spaced parallel relation and inclined slightly from the vertical toward the inlet end of the pipe whereby to provide a drag for the moving cotton, and to deflect a part of the current through the grid, said bars resilient and relatively thin to be vibrated by the air current for the purpose specified, and a box structure of which the grid forms the top for receiving foreign matter passing through the grid, said box having baffles extending transversely thereof between the grid and the bottom of the structure.

ture, and having clean-out doors in its bottom.

6. In combination with a pneumatic conveyer for cotton and the like, a cleaner including a box like structure forming the underside of the conveyer, and provided with a grid arranged between the structure and the conveyer in horizontal position and in substantial alinement with the bottom of the conveyer, said grid composed of plates arranged transversely of the conveyer in spaced parallel relation and inclining at their upper ends toward the inlet end of the conveyer, said plates resilient and relatively thin to be vibrated by the air current.

15 7. A pneumatic conveyer pipe cleaner adapted to be inserted in the length of a con-

veyer pipe, and including a grid to be inset in the bottom of the pipe in horizontal position to form a part of the wall thereof, said grid composed of relatively wide and resilient 20 plates sufficiently thin to be vibrated by the air current through the pipe, said plates arranged in parallel relation and rigidly connected at their ends, the grid adapted to be arranged with the plates transverse to the 25 conveyer, and with all of the plates inclining at their upper edges toward the inlet end of the conveyer.

Signed at Gastonia, N. C., in the county of Gaston and State of North Carolina, this 17th 30 day of November, A. D. 1927.

JASPER L. GRAY.
